BUTTON SHAPING MACHINE

Harry H. Knott, Washington, Iowa, assignor to
 American Pearl Button Company, Washington,
 Iowa

Application August 20, 1935, Serial No. 37,013

5 Claims. (Cl. 79—7)

The object of my invention is to provide a button shaping machine of simple, durable and inexpensive construction.

A further object is to provide a button tooling machine, comprising a tool head, which is readily adaptable to a conventional automatic button machine to replace the usual tool head provided thereon.

Another object is to provide an attachment for an automatic button machine designed to perform operations which replace costly hand operations and for making button patterns, which are not otherwise possible on an automatic machine.

Still a further object is to provide a means for smoother tooling and grinding of buttons, whereby designs can be made on the buttons without so much breakage of blanks and tools.

Still another object is to provide in combination with traveling button chucks, a tool head, which has a plurality of tools, one for each chuck, the parts being arranged for relative movement, so that the tools can periodically engage the button blanks, the blanks being either continuously rotated or periodically rotated for the purpose of forming either circular or circumferentially spaced designs on the button blank as desired.

Still another object is to provide a tool head arrangement with a novel driving mechanism for driving a plurality of tools carried thereby from a single belt pulley or other source of power.

Still a further object is to provide means for disposing of the cuttings from the tools, which means includes a manifold effective to produce equal suction on all tools by a single suction line.

With these and other objects in view, my invention consists in the construction, arrangement and combination of the various parts of my button tooling machine, whereby the objects contemplated are attained, as hereinafter more fully set forth, pointed out in my claims, and illustrated in the accompanying drawings, in which:

Figure 1 is a vertical, sectional view through one of the shafts of an automatic button machine with my attachment applied thereto.

Figure 2 is an enlarged, sectional view on the line 2—2 of Figure 1, showing a means for adjusting the tools with relation to the button blanks in the button chucks.

Figure 3 is an end elevation of a pair of bearings and a driving connection between the shafts in the bearings looking in the direction of the arrows 3 adjacent Figure 1.

Figure 4 is a sectional view on the line 4—4 of Figure 1.

Figure 5 is a sectional view on the line 5—5 of Figure 4, showing a partitioned manifold construction.

Figure 6 is a diagrammatic view showing the various positions of the button chucks, and indicating the positions of the buttons and the operations being performed thereon.

Figure 7 is a plan view of a button showing one design which can be cut therein by my tooling machine.

Figure 8 is a diagrammatic view showing a means for rotating the chucks when it is desirable to form a circular design on the button.

Figure 9 is a sectional view through a button illustrating a tool cooperating therewith for forming a concave button.

Figure 10 is a similar view showing a tool forming a convex button.

Figure 11 is a plan view of a button having a circular grooved design; and

Figure 12 is a sectional view similar to Figure 9 and taken on the line 12—12 of Figure 11 showing the button of Figure 11 in section and additionally showing the tool for forming this particular button.

On the accompanying drawings, I have used the reference numeral 10 to indicate a vertical shaft, which is rotatably mounted at one end of a button drilling machine and is driven by suitable mechanism. The shaft 10 is rotatably mounted at its lower end in a bearing 12 of a driving gear casing 14.

Secured to the shaft 10 is a sleeve 16 which has a pair of sprockets 18 and 20 for coaction with a pair of chains of peculiar construction. The chains referred to consist of links 22 and 24. There are two sets of these chains, one above the other, and the upper and lower links 24 are connected by yoke portions 26.

Both the upper and lower links 24 have bearings 28 encircling and thereby rotatably supporting tubular shafts 30. Portions 32 of the bearings 28 engage in depressions 34 in the sprockets 18 and 20, similar to the rollers of standard roller chains. Half bearing portions 36 of the bearings 28 extend only half way around the tubular shafts 30. Half bearings 38 are secured to the sprockets 18 and 20, and these half bearings meet the half bearings 36 of the bearings 28 when the portions 32 engage in the depressions 34. The half bearings 36 and 38 then comprise complete bearings for supporting and positioning the ends of the tubular shafts 30.

It may here be mentioned that there are two sets of sprocket wheels on a button drilling ma-

chine, the second set being indicated diagrammatically at 18a in Figure 6.

The yokes 26 of the links 24 merely act as carriers for maintaining the bearings 28 in proper spaced relation to each other for carrying the tubular shafts 30, as they are transported from one set of the sprocket wheels to the other set.

The tubular shafts 30 are provided with pulley portions 40.

10 Slidably mounted within the tubular shafts 30 are button holding chucks, comprising shafts 42, the upper ends thereof being split as at 44. The upper ends are also recessed at 46 to receive button blanks A.

15 Referring to Figure 4, the chuck shaft 42 at the position indicated as a is open to receive the blank A. By mechanism, not shown, the chuck is then contracted as at b to hold the button in the chuck.

20 The shafts 42 are provided with indexing cams 48 adapted to coat with a cam bar 50 (see Figure 6) having openings or notches 52 for the corners of the cam to rotate into and permit for each notch 52 a quarter revolution of the button chuck

25 for the purpose of rotating the button blank to the proper position for drilling as will hereinafter be described.

The foregoing is general automatic button drilling machine practice and forms no part of my invention.

In combination with the foregoing described automatic button machine, I provide a special tool head, which will now be described. It comprises a main sleeve 54 mounted on the shaft 10 and preferably vertically and rotatably adjustable relative thereto. For the vertical adjustment, I provide a pin 56 through the sleeve 54, through a vertical slot 58 of the shaft 10 and through a stub shaft 60.

40 The shaft 60 is vertically slidable in a bore in the upper end of the shaft 10 and vertical adjustment is imparted to it by a hand wheel 62 threaded on the shaft 60 and resting on a frame bar 64 of the machine.

45 Suitable means such as a set screw 66 is provided to lock the adjusting wheel 62 against rotation after it is once adjusted.

The means for rotatably adjusting the sleeve 54 relative to the shaft 10 comprises a split collar 68 (see Figure 2) clamped by a clamp screw 70 on the sleeve 54 and provided with a pair of arms 72. Set screws 74 are threaded through the arms 72 and engage opposite sides of a pin 75 extending upwardly from the sprocket 18, which it will be remembered is secured to the shaft 10 to rotate therewith. One set screw 74 can be loosened and the other one tightened, so as to rotatably adjust the sleeve 54 relative to the sprocket 18 for aligning tools carried by the sleeve with the chuck shafts 42 as will herein-after appear.

A secondary sleeve 76 is keyed to the main sleeve 54 and thereby retained against rotation relative to the main sleeve. The key is indicated at 78 and a set screw 80 is provided to tighten the key for the purpose of retaining the secondary sleeve 78 at a desired elevation relative to the main sleeve 54.

The secondary sleeve 76 has a plurality of circumferentially spaced faces 82 against each of which is positioned an angle-shaped bracket 84. The bracket is retained thereagainst by a cap screw 86 extending through a vertical slot 88 of the bracket, which permits vertical adjustment 75 of the bracket relative to the secondary sleeve 76.

For securing vertical adjustment, I provide a cap screw 90 having a flanged head 92 engaging in a notch 94 of the bracket 84, so that the cap screw when screwed inwardly or outwardly relative to the sleeve 76 will lower or raise the bracket 84 as desired. Thereafter the cap screw 86 can be tightened to retain the bracket in its adjusted position.

Against the lower face of each bracket 84, I provide a tool head 96 retained against the face 10 by a cap screw 98. The cap screw is located in an enlarged opening 100 of the bracket 84 to permit adjustment of the tool head 96 toward or away from the shaft 10.

For adjusting the tool head 96 inwardly or outwardly a flanged head cap screw 102 is provided, which is screwed into the tool head and has its flange engaging in a notch 104 of the bracket 84.

The tool head 96 can also be adjusted at right angles to a radial line by means of set screws 105 threaded in the angle bracket 84 and engaging opposite sides of the cap screw 98.

After the tool is properly adjusted inwardly or outwardly by rotating the cap screw 106, this cap screw 98 can be tightened for retaining the adjustment.

Each tool head has a tool shaft 106 journaled therein preferably in ball bearings, a pulley 108 being secured to the central portion of the shaft, 30 and tools such as indicated at 110 being secured to the outer end of the shaft. These tools may be either milled cutters or grinders as desired, and may be of any suitable shape for the particular work being tooled by them.

For driving the tool shafts 106, I provide pulley heads 112 mounted on radially extending arms 114 of the main sleeve 54. These rotatably support shafts 116 having pulleys 118 and bevel gears 120 mounted thereon. The pulleys 118 are 40 belted to the pulleys 108 by belts 122. The bevel gears 120 are driven by a bevel gear 124.

The bevel gear 124 is secured as by bolts 126 to a bearing cage 128. The bearing cage 128 is mounted by a ball bearing 130 to rotate relative 45 to the sleeve 54.

A pulley 132 is secured to the cage 128 and is driven from a suitable source of power as by a belt 134.

Thus the pulley is rotated about the sleeve 54 50 and imparts through the bevel gears 124 and 120 and the belts 122 rotation to all of the tools 110.

For carrying the cuttings away from the tools 110, I provide suction conduits 136 extending upwardly to a trough 138. The trough 138 is supported by bars 140 secured to the arms 114 and extending outwardly therefrom. Above the trough 138, I mount a manifold 142 having partitions 144 for dividing the manifold into a plurality of sections 146 in order to equally distribute the suction of the manifold. The partitions 144 are spaced approximately the same distance apart as the upper ends of the conduits 136, and the manifold 142 is connected with a suction or vacuum line 148 extending to the usual 65 centrifugal dust separator used as standard equipment in button making factories.

Rollers 150 extend from the side of the manifold 142 for riding on the peripheral edge of the trough 138, so as to closely position the lower 70 edge of the manifold 142 adjacent the trough.

I provide means tending to rotate the chuck shafts 42 and consisting of a strap 152 having its ends anchored as for instance on pins 154 and frictionally engaging the pulleys 40. On the 75

upper ends of the sleeves 30, I provide indexing cams 156, which are illustrated on the drawings as being triangular in shape. These are adapted for their flat faces to travel along guide bars 158 and 160 to prevent the chucks from rotating.

The guide bar 160 is provided with a pair of openings or notches 162 for the points of the indexing cams 156 to rotate into, due to the action of the strap 152, as best shown in Figure 6, at 10 positions marked *c* and *d*.

The bar 160 as illustrated more in detail in Figure 4 has its sections supported by rods 164 and urged to contact with the cams 156 by springs 166. Lock nuts 168 are provided for adjusting the bar 160 toward or away from the cams as found desirable.

In some instances, I desire to rotate the chucks rather than retaining them stationary and indexing them. This can be done by providing a belt 170 (see Figure 8) trained around idlers 172 and over a drive pulley 174. The belt contacts with the pulleys 40, so that as the belt is driven the pulleys also are driven, and thereby the chucks and the button blanks A rotate.

25 Practical operation

In the operation of my device as set up in Figures 1 and 6, a button blank A1 is placed by the operator in position in a chuck and then travels 30 along the bar 158 and the bar 160 in the direction of the arrow 176. The cams 156 retain the button blank against rotation and it starts to swing around the shaft 10. At the position indicated at A2, a cam 178 (see Figure 1) raises the chuck, causing the blank to be engaged by the tools 110, which register with the blank, and a pair of grooves 180 are cut therein.

The cam 178 then permits the chuck to move 40 downwardly again out of engagement with the tools 110 and at the position *c*, the blank is being rotated a third of a revolution. At the position A2a, two more grooves 182 are cut, and this cycle is repeated, the blank being turned another third turn at the position *d* and two more grooves 45 184 being cut at the position A3.

The blank then travels through the button drilling machine for further operations to be performed thereon, which operations are old and do not form any part of my present invention. I 50 will describe them, however, as they will make the description of the operation of my invention clear.

At the position A4, a fish eye 186 is cut in the blank. At the position A5, one thread hole 188 55 is drilled in the blank. At the position *e*, the notch 52 of the bar 50 rotates the blank a quarter of a revolution so that at the position A6, the fish eye and drilled hole will assume the position illustrated.

60 Another quarter turn is then given to the blank at the position *f*, and at the position A7, a second hole 190 is drilled in the blank. Further positions *g*, *h* and *j* illustrate three more quarter turns of the blank, so that the cams 48 and 156 65 will be in their initial position for discharge of the button at A8, and reception of another button blank at A1.

It will be obvious that by providing triangular cams 156 and giving the blanks a third of a rotation at positions *c* and *d*, a six-sided design, such as shown in Figure 7 can be tooled in the button blank.

By modifying the shape of the tools 110, other designs can be produced.

75 By providing square instead of triangular

cams 156, octagonal or square shapes can be tooled in the buttons.

It is therefore obvious that a number of designs can be produced by using various shapes of cams and various bars 160 for rotating the 5 chucks the required fractions of a revolution, the cam 178 also being designed for the particular button design being tooled.

Circular designs, such as shown in Figures 9, 10, 11 and 12 can be cut by tools 110a, 110b, and 10 110c, and by rotating the chucks, by the construction shown in Figure 8 rather than by indexing them. This gives different annular designs depending upon the particular tool used.

The buttons illustrated in Figures 7, 9, 10, 11 15 and 12 are merely illustrative, as it is obvious that many other designs can be worked out and automatically tooled with my construction, thereby eliminating expensive hand tooling as now practiced.

The tool heads 96 are universally adjustable on the clamps 84 for accurately aligning them with the centers of the chucks or positioning them off-center if a design calling for such positioning is to be tooled on the blanks.

The tool heads are individually vertically adjustable due to the individual mounting of each bracket 84 on the sleeve 76, and are simultaneously vertically adjustable by adjusting the sleeve 76 vertically relative to the main sleeve 30 54. Such an adjustment is particularly desirable in order to tighten or loosen the belts 122 as required.

The entire assembly carried by the main sleeve 54 is then vertically adjustable by manipulating 35 the hand wheel 62, so as to accommodate thicker or thinner button blanks or produce deeper or shallower cuts as desired.

My attachment is readily applicable to the usual type of automatic button drilling machine 40 to replace tools now provided thereon, and provides a means for making patterns, which are otherwise not possible on an automatic drilling machine, and possible only by a special hand operation, which requires more time and expense 45 for production of the design on the button.

Various changes as suggested and others may be made without departing from the real spirit and purpose of my invention, and it is my intention to cover by my claims, any modified forms 50 of structure or use of mechanical equivalents, which may be reasonably included within their scope.

I claim as my invention:

1. A button tooling machine comprising a plurality of reciprocably mounted traveling chucks and a traveling tool head, having a tool for engagement with a blank held in each chuck for tooling a design therein and on an axis at right angles to the axis of the blank, means for retaining said chucks against rotation while said design is being tooled therein, means for reciprocating said chuck a plurality of times for tooling a plurality of said designs in the blank held thereby, and means for rotating said chucks between 60 the tooling operations to space said designs circumferentially relative to said blanks.

2. In a tooling machine, a plurality of chucks mounted for rotation about an axis, a tool head mounted for rotation simultaneously therewith 70 about said axis, a tool on said head for each chuck, means for relatively moving said chucks and tools a number of times to cause the tools to engage and disengage blanks held by said chucks a number of times, and means for rotat- 75

ing said chucks a predetermined fraction of a revolution between said times, said means comprising pulleys for rotating said chucks, a stationary belt frictionally engaging said pulleys to bias them toward rotation in one direction, cams connected with said pulleys and means for engaging the lobes of said cams to normally retain said cams against rotation, said means having portions to receive said lobes to permit rotation of said cam under the influence of said belt upon said portions receiving said lobes.

3. In a tooling machine, a plurality of chucks mounted for rotation about an axis, a tool head mounted for rotation simultaneously therewith about said axis, a tool on said head for each chuck, said tools having axes of rotation at right angles to the axis of rotation of said tool head, means for relatively moving said chucks and tools to cause the tools to engage and disengage blanks held by said chucks, a suction conduit adjacent each tool for removing cuttings therefrom, said conduits traveling with said head, and a stationary manifold having partitioned sections spaced for registry of one with each conduit during rotation of the conduits and while the tools therefor are cutting blanks.

4. In a tooling machine, a plurality of chucks mounted for rotation about an axis, cams for indexing said chucks, a tool head mounted for rotation simultaneously with said chucks about said axis, a tool on said head for each chuck, said

tools having axes of rotation at right angles to the axis of rotation of said tool head, means for relatively moving said chucks and tools to cause the tools to engage and disengage blanks held by the chucks, said chucks having other cams, means for engaging said other cams and thus indexing said chucks for other operations, and means for rotating said chucks to their original positions, whereby said first operations are performed thereon in a predetermined relation to 10 said other operations.

5. A button tooling machine comprising a plurality of reciprocably mounted traveling chucks and a traveling tool head, having a tool for engagement with each chuck for tooling a design in 15 a blank held by the chuck, means for retaining said chucks against rotation while said design is being tooled therein, means for reciprocating said chuck a plurality of times for tooling a plurality of said designs in the blank held thereby, and 20 means for rotating said chucks between the tooling operations to space said designs circumferentially relative to said blanks, said means comprising a frictionally operable element biasing said chucks to rotate, cams and tracks engaged thereby to normally retain said cams against rotation due to such bias, said tracks having notches to receive portions of said cams and thereby permit rotation due to such bias at predetermined points of travel.

HARRY H. KNOTT.
